FIG. 9.

FIG. 10.

FIG. 11.**FIG. 12.**FIG. 1 is a top plan view of a dry cleaning machine showing my new design;

FIG. 2 is a front elevational view thereof;

FIG. 3 is a left side elevational view thereof;

FIG. 4 is a right side elevational view thereof;

FIG. 5 is a top plan view of a modified form of the design shown in FIG. 1;

FIG. 6 is a front elevational view thereof;

FIG. 7 is a left side elevational view thereof;

FIG. 8 is a right side elevational view thereof;

FIG. 9 is a top plan view of another modified form of the design shown in FIG. 1;

FIG. 10 is a front elevational view thereof;

FIG. 11 is a left side elevational view thereof; and

FIG. 12 is a right side elevational view thereof;

FIG. 13 is a vertical cross-sectional view thereof, taken on the line 13—13 of FIG. 2.

The rear not shown is substantially plain.

My design for a dry cleaning machine is characterized by the annular beading located on the peripheral portion

of the door and the adjacent box-like members at the upper front thereof, as shown.

The door portion of the machine has the same appearance in the modified forms, as indicated in FIG. 13.

I claim:

The ornamental design for a dry cleaning machine, substantially as shown and described.
